UNITED STATES PATENT OFFICE

101,808

DESIGN FOR A ROLLER SKATE

Tallie C. Wall, Mount Vernon, Ill.

Application October 4, 1935, Serial No. 61,915

Term of patent 3½ years

To all whom it may concern:

Be it known that Tallie C. Wall, a citizen of the United States, residing at Mount Vernon, in the county of Jefferson and State of Illinois, has invented a new, original, and ornamental Design for a Roller Skate, of which the following is a specification, reference being had to the accompanying drawing, forming a part thereof, in which

Figure 1 is a side elevational view of a roller skate embodying the new design; and

Figure 2 is a top plan view of the roller skate shown in Figure 1.

I claim:

The ornamental design for a roller skate, as shown.

TALLIE C. WALL.
